UNITED STATES PATENT OFFICE.

HENRY ROBERTS, OF HYDEPARK, CALIFORNIA.

COTTON-PICKER'S KNEE-PAD.

No. 893,547.

Specification of Letters Patent.

Patented July 14, 1908.

Application filed March 18, 1907. Serial No. 363,120.

To all whom it may concern:

Be it known that I, HENRY ROBERTS, a citizen of the United States, residing at Hydepark, in the county of Los Angeles and 5 the State of California, have invented a new and useful Cotton - Picker's Knee - Pad, of which the following is a specification.

It is customary in cotton fields for each 10 cotton-picker to be supplied with a bag of great length, usually about twelve feet long, which is fastened to his body, and which he allows to drag on the ground behind him, while he advances on his knees between two 15 rows of cotton, and gathers the cotton from the rows and puts the same in the bag; continuing across the field, to and fro, until the bag is filled. Such bags when full usually contain eighty pounds, more or less, of cotton, and therefore the labor of dragging 20 such bag over the ground and between the rows places a severe burden upon the knees of the picker, and it is necessary that some character of pad be worn upon his knees in order to enable him to perform his work 25 with any degree of satisfaction or success.

It is of the objects of this invention to provide knee-pads which will afford to the cotton-picker maximum ease, and which will protect his knees and clothing from abrasion 30 and wear; which are not liable to work loose; which will stay firmly in position while the wearer kneels and also while he is walking; that are cheap, light, durable, and easily constructed, and that are easily applied to 35 and removed from the leg.

Heretofore, knee-pads for cotton-pickers have been variously constructed and variously padded, some being provided with a stiff shoe or base with an internal padding 40 of horse-hair or other padding material. An objection I have noted relative to all such pads is that the material of the pad will set to the form of the knee, and that slight irregularities therein will impress the flesh of 45 the knee, causing great discomfort and inconvenience to the wearer.

An object of my invention is to provide a knee-pad which will not become set to the form of the knee, but will constantly afford 50 a resilient cushion for all parts of the knee which bear down upon the pad. This I accomplish by providing a shoe in which an air bag is contained and held in position to support the downward pressure of the knee.

In experimenting for the purpose of perfecting this invention I have found it necessary to make provision against tightly binding the leg, and to also provide for holding the air-bag against displacement, and in order to accomplish this in the most satisfactory manner, I have provided a shoe open 55 at the top and having a forwardly deepening cavity above a rearwardly thickened sole for holding an air-bag having its greatest thickness at that portion of the shoe where 60 the weight of the knee presses most heavily.

It is to be understood that the invention may be used in other work than cotton-picking; such for instance as for floor-polishers' use, and in such cases a soft covering may be 65 supplied for the bottom of the shoe, but I shall herein describe and show the invention without such soft sole, as it is advisable in field work to provide a sole of very durable material, as sheet metal, or the like.

The accompanying drawings illustrate the invention in the form I find most satisfactory.

Figure 1 is a perspective view of a cotton-picker's knee-pad embodying my invention in use attached to a knee. Fig. 2 is a longitudinal mid-section of the device shown in Fig. 1, detached, and omitting the lacings. Line x^2 , Fig. 3, indicates the line of section. Fig. 3 is a fragmental, sectional elevation on line x^3 , Fig. 2, looking in the direction of the 85 arrow. Fig. 4 is an enlarged, fragmental, sectional detail of one of the side walls of the shoe shown in Fig. 3. Fig. 5 is a plan of the knee-pad detached, omitting the lacings. Fig. 6 is a fragmental, sectional detail showing one form of valve for the air-bag. Fig. 7 is a fragmental, sectional detail showing another form of the valve for the air-bag.

1 is a shoe open at the top and rear and provided with a perforation 2 in one of its 95 walls, as the front wall 3. Means 4, 5, 6, are provided for fastening the shoe to the knee, the same comprising flaps to be secured by lacings a , b , inserted through eyelets c , c' , appropriately located in said flaps.

7 is a flexible shield inside the shoe, and 8 is an air-bag inside the shoe between the shield 7 and the sole 9 which is wedge-shaped; the large end of the wedge being at the rear, as clearly seen in Fig. 2. Said air-bag is provided with a nipple-valve 10 at said perforation 2. Said nipple-valve 10 preferably extends through the perforation 2 at the front 105

end of the shoe and is provided with the usual cap 11, and may be protected by an external flap 12 fastened to the wall of the shoe above the perforation 2 to extend down over the 5 nipple. Said flap may have a recess 13 to accommodate the cap of the nipple. It is desirable that the nipple and cap form as slight a projection as possible, and with this object in view the valve may be made short 10 outside of the air-bag, an inner valve-flap 14 being provided in some instances to form the closure of the valve; or any ordinary construction of a bicycle-valve, as shown at 15 in Fig. 7, may be used.

15 The shoe 1 is preferably made of sheet metal appropriately formed with a flat-bottom sole 9, front wall 3, and side walls *d*, *e*. The sole being made of sheet metal, is hollow, the top thereof being formed of a strip *f* bent 20 in between the walls *d*, *e*. The flexible shield 7 and the flaps 4, 5, 6, are preferably formed of a single sheet of strong, flexible material, as canvas, the same being bent upon the side and front walls and appropriately secured by 25 sheet-metal clips or strips, as 16, 17, the lower edges of the first two of which trend downward rearwardly from the level of the bottom edge of strip 18 so as to cause the shield to slope backward rearwardly from the 30 front wall toward the level of the top of the rear thick end of the sole 9, so as to form a forwardly enlarged wedge-shaped cavity between the wedge-shaped sole and the flexible shield 7, thereby tending to enable the knee 35 to press forward the air-bag 8 contained in the space between said sole and shield. Said clips or strips of sheet metal are secured in place by means of rivets 19, 20, 21, thereby firmly holding the canvas in place.

40 The clips 16, 17, for the side walls are **U**-shaped and are inverted over the top edges of the side walls after the canvas wings 4, 5, forming the shield and flaps have been folded over the top edges of said side walls. When 45 the **U**-shaped clips are firmly brought into position to hold the shield appropriately, they are fastened in place by rivets 19. The upper rivets 20 for securing the strip 18 may extend through the flap 12 as well as through 50 the canvas for the flap 6, and through the strip 18, thus holding all firmly to the front wall 3.

The inside wings of the clips 16, 17, are cut away, as shown at 22, above the rear thick 55 portion of the sole, so that the shield 7 may be lifted up sufficiently from the thick sole to insert the air-bag into place and bring its nipple 10 through the perforation 2. The sole is provided with perforations 23 through 60 which lacings 24 may be passed to secure the rear end of the shield 7 to the sole and prevent the displacement of the air-bag.

In practical use, the air-bag will first be inflated; then the wearer will place his knee

in the pad and secure the same by the lacings 65 *a*, *b*, bringing the shield 6 up in front of the leg. The pad will then be ready for use. By these means the pad is provided with a cushioning device which will not set to the form of the knee, and will not irritate the 70 knee by any irregularities, and the pad will not become displaced. In case the air-bag should become deflated, the shield will temporarily support the knee with comfort until the bag can be reinflated. Enough slack is 75 given to the shield 7 to allow it to bow upward as indicated in Figs. 2 and 3, when the air-bag is fully inflated, thus allowing the shield to be resiliently supported by the air-bag.

80 What I claim is:—

1. A cotton picker's knee-pad comprising a shoe adapted to be fastened to the leg at the knee, a flexible shield in the shoe attached at a distance above the floor to the 85 walls of the shoe to form a support for the knee, and an air-bag in the shoe between the shield and the sole of the shoe to normally support the shield and the knee.

2. A cotton picker's knee-pad comprising 90 a shoe open at top and rear, means for fastening the shoe to the leg at the knee, a flexible shield in the shoe fastened to the walls thereof at front and sides at a distance above the floor of the shoe to form a support for the 95 knee, an air-bag in the shoe between the sole and the shield to normally support the shield and knee, and means for temporarily fastening the rear of the shield to the rear of the shoe-sole.

100 3. A cotton picker's knee-pad comprising a shoe open at top and rear, means for fastening the shoe to the leg at the knee, a flexible shield inside the shoe fastened to the sides thereof, the rear end of the shield and the 105 sole being perforated, an air-bag in the shoe between the shield and the shoe-sole, and a lace in the perforation to fasten the rear of the shield to the shoe.

4. A knee shoe provided with an air cushion, means at the rear to go around the leg below the knee to fasten the shoe to the leg, and a shield at the front of the shoe to protect the front of the leg and to connect the front of the shoe with the leg.

110 5. A knee shoe provided with a flat sole the top of which slopes forwardly and a wall extending upward at the edges of the sole front and sides to form a cavity deeper at front than rear, means for fastening the shoe 120 to the leg, an air cushion inside the cavity, and means to retain said bag therein.

6. A knee shoe provided with a flexible shield above the sole of the shoe, an air bag under the shield provided with a nipple valve, the nipple thereof extending through 125 the wall of the shoe, and a flap provided inside the shoe as a closure for the valve.

7. A knee shoe provided with a flexible shield above the sole of the shoe, an air-bag under the shield provided with a nipple-valve, the nipple thereof extending through 5 the wall of the shoe, and a flap outside the shoe to cover the nipple of the valve.

In testimony whereof, I have hereunto set

my hand at Los Angeles California this 2nd day of March 1907.

HENRY ROBERTS.

In presence of—

JAMES R. TOWNSEND,

M. BEULAH TOWNSEND.
